(57) **CLAIM**

The ornamental design for a grip for soldering iron, as shown and described.

DESCRIPTION

FIG. 1 is a perspective view of a grip for soldering iron; FIG. 2 is a front view thereof, the opposite side being a mirror image of the side shown herein; FIG. 3 is a left side view thereof; FIG. 4 is a right side view thereof; FIG. 5 is a top view thereof, the opposite side being an identical image of the side shown herein; FIG. 6 is an enlarged left side view thereof; and, FIG. 7 is an enlarged right side view thereof.
The broken line portions of the grip for soldering iron in the drawings depict unclaimed environmental subject matter.
